UNITED STATES PATENT OFFICE.

JAMES L. BURNHAM, OF SACO, MAINE.

HANK REGISTER.

Application filed March 30, 1922. Serial No. 548,031.

To all whom it may concern:

Be it known that I, JAMES L. BURNHAM, a citizen of the United States, residing at Saco, in the county of York and State of 5 Maine, have invented certain new and useful Improvements in Hank Registers; and I do declare the following to be a full, clear, and exact description of the invention, such as will enable others skilled in the art to 10 which it appertains to make and use the same.

This invention relates to an improved hank register for use upon roving, spinning and spooling machines and one object of the 15 invention is to provide a register in which there will be provided a stationary plate having inner and outer sight openings formed therein beneath which will be mounted concentric dials which rotate in 20 the proper timed relation and will accurately indicate the number of hanks and fractions thereof. By having the plate stationary and provided with sight openings across which pointers extend, the rotating 25 dials will be covered except the portions which show through these openings. It will thus be seen that the counter can be very easily read by simply observing the dials through the openings of the stationary plate 30 and ascertaining the number of hanks and portions thereof by observing where the pointers extend with respect to the dials.

Another object of the invention is to provide a hank register in which the plate having the sight openings formed therein may be carried by the post about which the operating mechanism for the dials is mounted.

Another object of the invention is to so 40 construct the dial-carrying and operating gearing that it may be driven from the driving shaft of the device and the two dials moved in the same direction concentric to each other and one rotate at a greater rate 45 of speed than the other.

Another object of the invention is to so construct this device that the means for carrying and operating the dials may be bodily removed from the housing or casing 50 of the device when so desired.

This invention is illustrated in the accompanying drawings, wherein:

Figure 1 is a view of the complete register ready for use.

55 Figure 2 is a longitudinal sectional view through the register.

Figure 3 is a transverse sectional view taken along the line 3—3 of Fig. 1.

Figure 4 is a view showing the housing or casing with the mechanism normally positioned therein removed. 60

Figure 5 is a view looking at the inner face of the dial-carrying and operating means.

Figure 6 is a plan view of the plate which is secured to the post of the casing and provided with the sight openings. 65

Figure 7 is a plan view of the dial-carrying and operating means with the inner dial removed. 70

This improved hank register is provided with a casing or housing 1 which is open at one end and internally threaded so that the cover 2 may be screwed into place. This cover 2 is in the form of a ring which carries a transparent sheet 3 so that with the cover in place to keep out dust, the register may be read. This casing or housing is provided with a side compartment 4 having a bearing 5 at one end which will be provided 80 with a passage to receive the bushing 6 through which will extend the drive shaft 7. This drive shaft 7 carries a gear wheel 8 for operative connection to the machine and at its inner end carries a worm 9 which is held 85 in place by a collar 10. A post 11 is provided in the housing or casing 1 and is provided with a reduced end portion 12 which extends through an opening formed in the bottom of the housing and is threaded to 90 receive the securing nut or mounting bracket 13. Before the reduced end portion 12 of the post is passed through the opening in the bottom of the housing, a gear disk 14 will be placed upon this reduced end and secured so that when tightened by the securing 95 nut or bracket 13, the post and the gear will be rigidly mounted in the housing and neither will be permitted to turn.

Within the housing, there has been provided the main rotatable element which is in the form of a large worm gear 15. This large worm gear 15 is provided with a hub sleeve 16 which forms a hub extension and is of such length that when the gear 15 is placed within the housing, the sleeve 16 will extend from the outer end of the post 11 to a point in close contact with the stationary gear disk 14. A small disk 17 is carried by the outer end portion of this sleeve 16 and will be marked to provide the inner dial. 105 This disk may be removed from the hub 110

sleeve when necessary but when in place will turn with the sleeve and large gear. A set-screw 18 is provided so that this hub sleeve may be removed from the gear 15 when it is 5 desired to renew the same.

The second dial 19 is positioned beneath and concentric to the dial 17 and is provided with a ring or collar 20 which fits upon the hub extension 21 of the gear 22, a set-screw 10 23 being provided to securely hold the collar in place upon the hub extension of the gear. This gear 22 fits loosely upon the sleeve 16 and it will thus be readily seen that the dial 19 may have rotation independent 15 of the dial 17. In order to impart rotary movement to the dial 19, as the gear 15 rotates, there has been provided a stem 24 which is journaled in the gear 15 and carries gears 25 and 26 at its ends. These gears 25 20 and 26 are rigid upon the stem 24 and mesh one with the rigid gear 14 and the other with the gear 22. It will thus be seen that as the worm gear 15 is rotated, the gear 22 will receive rotary movement independent 25 of the gear 15 and the two dials will have independent rotary movement with one moving faster than the other and in timed relation to it. The plate 27 is rigidly secured to the end of the post 11 by means of the 30 securing screw 28 and is provided with inner and outer sight openings 29 and 30. The sight opening 29 is positioned above the dial 17 and the sight opening 30 is positioned above the dial 19. Each of these openings is 35 cut so as to provide a pointer 31 thus permitting the dials to be accurately read.

When this counter is in use, it will be put in place in connection with the machine so as to be driven by a co-operating worm on 40 the machine. The drive shaft 7 will thus be rotated and as this drive shaft rotates, rotary movement will be transmitted to the worm-gear 15 thus causing the inner dial to be rotated. As this gear 15 rotates, the gear 45 25 through engagement with the rigid gear 14 will cause the shaft 24 to be slowly rotated. The gear 26 carried by this shaft 24 through engagement with the gear 22 will cause this gear and the dial 19 to slowly 50 rotate. The dial 19 registers the number of hanks and the dial 17 which shows through the sight opening 28 registers fractions of a dial. Since the plate 27 is stationary and the two dials move beneath it, the dials can 55 be readily viewed through the openings and a proper reading obtained. There has been provided a counter which is so constructed that it will operate very efficiently and may be easily read and there has further been 60 provided a counter so constructed that it may be readily taken apart and put together again when it is desired to repair or clean the counter.

I claim:

65 1. A counter of the character described

comprising a casing, a stationary plate in the casing provided with inner and outer sight openings, an element rotatably mounted in the casing and carrying a dial viewed through the inner sight opening, a drive 70 shaft for said rotatable element, a gear disk rigid in the casing and positioned about the axis of said rotatable element, a second rotatable element rotatably carried by the first about its axis and carrying a dial positioned concentric to the first dial and viewed through the outer sight opening of said plate, and means carried by the first rotatable element and actuated by the rigid gear disk for imparting rotary motion to the 75 second rotatable element during rotation of the first.

2. A counter of the character described comprising a casing, a drive shaft, a post in the casing, a rigid gear about the post, 80 a plate secured to the post and having inner and outer sight openings, an element in the casing rotatable about the post and rotated from the drive shaft and carrying a dial viewed through the inner sight opening of the plate, a second element rotatably mounted in the casing for rotation concentric to the first rotatable element and carrying a dial viewed through the outer sight opening of the plate, and means carried by the first 85 mentioned rotatable element and actuated by the rigid gear for imparting rotary movement to the second rotatable element independent of the first during rotation of the first.

100 3. A counter of the character described comprising a casing, a drive shaft, a post in the casing, a rigid gear about the post, a plate secured to the post and having inner and outer sight openings, a main gear rotatable about the post and driven from the drive shaft and having a hub extension carrying a dial visible through the inner sight opening of the plate, a gear loose upon the hub extension of the main gear and carrying a dial concentric to the first dial and visible through the outer sight opening of the plate, a stem journaled in the main gear, and gears rigidly carried by the stem upon opposite sides of the main gear and meshing one with the rigid gear and the other with the disk carrying gear loose upon the hub extension of the main gear.

105 4. A counter of the character described comprising a casing, a drive shaft extending into said casing, a post rigid in the casing, a plate secured to the post and having inner and outer sight openings, a gear disk rigid in said casing about said post, a main drive gear loose upon said post and rotated from said drive shaft, a sleeve extending from said drive gear about said post and carrying a dial viewed through the inner sight opening of said plate, a collar loose upon said sleeve and having a gear at its inner 110 115 120 125 130

end and at its outer end a dial concentric to the first dial and viewed through the outer sight opening, a stem journaled in said drive gear, and gears rigid upon said stem 5 with one meshing with the gear of said collar and the other meshing with the gear disk rigid in the casing about the post.

5. A counter of the character described comprising a casing, a drive shaft journaled 10 in said casing and having a worm upon its inner end, a stationary post in said casing, a gear disk rigid in said casing about said post, a relatively large worm gear in the casing turning about the post and meshing 15 with said worm, a sleeve extending from said worm gear about the post, a dial car-

ried by said sleeve and turning with the sleeve and worm gear, a collar loose upon said sleeve between the worm gear and dial and having a gear at its inner end and a 20 dial at its outer end concentric to the first dial, a stem journaled in the worm gear, gears rigid upon the stem and meshing one with the gear of said collar and the other with the gear disk about said post, and a 25 plate rigidly carried by said post and cut to provide sight openings and pointers in operative relation to the dials.

In testimony whereof I have hereunto set my hand.

JAMES L. BURNHAM.
